UNITED STATES PATENT OFFICE.

ANTHONY CHARLES GUNTZER, OF NEW YORK, N. Y.

CANDELABRUM.

No. 838,619.

Specification of Letters Patent.

Patented Dec. 18, 1906.

Application filed March 3, 1906. Serial No. 304,071.

To all whom it may concern:

Be it known that I, ANTHONY CHARLES GUNTZER, a citizen of the United States, and a resident of the city of New York, borough of Manhattan, in the county and State of New York, have invented a new and Improved Candelabrum, of which the following is a full, clear, and exact description.

The purpose of the invention is to provide a candelabrum wherein the body portion is in the form of a cross revolvably mounted upon an adjustable standard and to provide the said standard with removable legs at its base and also to provide simple and readily-applied locking devices for the legs.

Another purpose of the invention is to construct the cross forming the body in sections readily removable, and which when assembled will not show their points of connection at the front, and to provide means for securing the sections firmly in place, which means can be quickly and conveniently applied and are not visible at the front of the body.

Another purpose of the invention is to provide the body with series of tapering sockets, and the candle-holders, and the corpus and scroll, if they are used, with tapering shanks adapted to enter and have frictional engagement with the inner walls of the sockets, enabling said parts to be quickly and firmly placed in position or removed and the various factors to be interchangeably employed.

Another purpose of the invention is not only to provide an adjustable standard for the body, but also to construct the standard in detachable sections, enabling such a number of parts forming the candelabrum to be separated one from the other, so that said parts can be placed in a comparatively small box for transportation.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a front elevation of the improved candelabrum. Fig. 2 is an edge view of the body of the candelabrum and a side elevation of a portion of the standard. Fig. 3 is a longitudinal section through a portion of the body of the candelabrum and parts carried thereby, the section being taken at a

central point, and a sectional side elevation of a portion of the standard. Fig. 4 is an enlarged rear view of those portions of the members of the body which connect, the fastening devices for such parts being removed. Fig. 5 is a vertical section through the lower portion of the standard and a side elevation of one of the legs, illustrating the manner in which the legs are attached to the standard. Fig. 6 is a horizontal section taken practically on the line 6 6 of Fig. 5. Fig. 7 is a transverse section through one of the arms of the body, the section being taken adjacent to the outer end of the arm; and Fig. 8 is a rear elevation of an arm of the body at its outer end portion, a part being in section, the said view also showing a rear elevation of an ornament for the arm and the manner in which the ornament is applied thereto.

The improved candelabrum may be said to consist, primarily, of a body-section A, a standard B for the body-section, and legs C for the standard. The body-section A is in the form of a passion-cross, as is illustrated in Figs. 1 and 2, and is constructed of any suitable material and in three separatable sections—namely, a transverse section a and upper and lower longitudinal sections a' and a''. Each section of the body at its side edge is provided with a rearwardly-extending flange 10, and each flange 10 has a projection 11 upon its inner face at its rear edge. In each projection 11 a longitudinal groove 12 is produced, as shown in Figs. 3 and 7, so that the sections of the body A may be given a box formation, when it is desired, by sliding back plates (not shown) in the grooves 12 of the sections, thus producing a chamber in which electric wires may be laid and concealed when the candelabrum is to be lighted by electricity. The ornaments 13 at the outer ends of the arms or sections of the cross-body are removably connected therewith, as shown in Figs. 7 and 8, by attaching pins 14 to the ornaments, which pins are slid into the spaces between the back of the arms or sections of the body and the projections 11 from their flanges 10, as is particularly shown in Fig. 7.

At the central portion of the transverse section a of the body A an opening 15 is made in the upper flange 10 of said section, and a registering opening 16 is produced in the lower flange, as is shown in Fig. 3. A threaded bolt 17 is passed rearwardly through the center of the said section a between the open-

ings 15 and 16, as is also shown in Fig. 3. The head of this bolt, which appears at the front of the said body-section, may be either plain or ornamental.

5 The upper longitudinal section or member a' of the body A is provided at its lower end with a flat lip 18, (shown in Figs. 3 and 4,) which lip 18 is usually convex at its lower end and is of sufficient size to slip readily into 10 and through the opening 15 in the transverse member a of said body. In the lower edge of the lip 18 a recess 18^a is made, which receives a portion of the bolt 17, and an aperture 18^b is made in the lip 18 at a point 15 above the recess 18^a. The lower longitudinal member a^2 of the cross-body is also provided with a flat lip 19, adapted to enter and pass through the lower opening 16 in the central member a , as is likewise shown in Figs. 3 20 and 4. The upper edge of the lip 19 is preferably convex, and in the said convex edge a recess 19^a is produced, adapted to receive the lower portion of the said bolt 17. An aperture 19^b is made in the lip 19 at a point below 25 the recess 19^a, the apertures 18^b and 19^b being in vertical alinement with each other and with the bolt when the lips 18 and 19 have been introduced into the transverse member a of the cross-body. When the lips 30 18 and 19 have been introduced into the member a to their full extent, the ends of the flanges 10 on the upper and lower members a' and a^2 abut smoothly and almost imperceptibly against the flanges on the transverse member a , as is indicated at the upper 35 portion of Fig. 4.

The members of the cross-body are held in their assembled position by means of a washer 20, apertured to receive the threaded 40 portion of the bolt or pin 17, which washer is provided with lugs 21, so placed that said lugs will enter the apertures 18^b and 19^b of the lips 18 and 19, as is shown in Fig. 3, and then a thumb-nut 22 or its equivalent is 45 screwed upon the threaded end of the bolt 17 to a firm bearing against the said washer 20, as is also shown in Fig. 3.

50 A post 23 is attached to or formed integral with the under surface of the upper portion of the lower member a^2 of the cross-body at a point centrally between its sides. The said post is vertical; but the body has an inclination with respect to said post, the inclination of the body being from the top downward and outward. In fact, the inclination 55 of the body toward the perpendicular post 23 is more or less acute, as is clearly shown in Figs. 2 and 3. The said post 23 has a reduced lower end portion 24, thus producing 60 a shoulder 25. The post 23 is circular in cross-section, and its reduced end 24 is made to loosely enter a socket 26, formed in the upper end of the upper section b of the standard B, as is clearly shown in Fig. 3, the 65 shoulder 25 of the post engaging with the

upper end surface of the said section b . Thus it will be observed that the body A can be readily lifted from engagement with the standard B and can be turned thereon, as desired.

70 A number of tubes 27 are either formed integral with the members of the cross-body A or are attached thereto; but the tubes extend above and below the upper and lower faces of said members, as is clearly indicated 75 in Fig. 3. Said tubes are open at the top and bottom, and the bores of the tubes are tapering, being narrowest at their lower ends, as is also shown in Fig. 3. These tubes 27 80 constitute a series of sockets and are placed in a vertical position—that is, parallel with the standard B—but extend upwardly at an angle to the front face of the said cross-body, as shown in Figs. 1, 2, and 3. These sockets are preferably thirteen in number, although 85 any desired number may be employed, and they are arranged one above the other on the longitudinal members a' and a^2 of the cross-body and side by side on the transverse member a .

90 The socket-tubes 27 are adapted to receive candle-holders D or are adapted to hold in position a corpus D' and likewise a scroll D² when these two are employed. To such end the candle-holders are provided with tapering shanks 28, adapted to fit into the socket-tubes 27 in close frictional engagement therewith, as is shown in Fig. 3. The scroll D² is provided with similar shanks adapted to enter two adjacent socket-tubes 27, as is indicated in Fig. 1, while the corpus D' has a shank 29 extending from the bottom central portion of the image and of the same character as the shank 28 of a candle holder or cup, and when the shank 29, extending from the corpus D', enters a socket-tube 27, as is 100 shown in Figs. 2 and 3, the body portion of the image covers one of the socket-tubes and the feet rest upon another socket-tube. The socket-tube upon which the feet of the image rest is concealed by a housing 30, attached to the foot-section of the image. When a corpus is employed, a holy-water font 31 is likewise used, which is also provided with a tapering shank. When this holy-water font is 105 employed, its shank is made to enter the last or lowest socket-tube 27 of the body, as is shown in Figs. 1 and 2. When said corpus is used, it is placed upon the upper portion of the lower member a^2 of the body, the arms of the corpus extending up and resting against the transverse member a , and the scroll D² is located over the head of the corpus, its tapering shanks being made to enter the socket-tubes 27 at each side of the center of said member, as is shown in Fig. 1. Two candle holders or cups are located at each side of the figure on the said transverse member a . Two candle holders or cups are likewise located on the upper longitudinal member a' 110

of the body, while below the image or figure | the shank of a single candle-holder and that of the holy-water font 31 are made to enter the lowermost socket-tubes 27 on the lower 5 member b^2 . When the corpus, the scroll, and the holy-water font are not employed, each socket-tube 27 is utilized to support a candle holder or cup.

The standard B comprises an upper member b , a second lower member b' , a third lower member b^2 , and a base member b^4 . In the construction of these members the upper member b is preferably of the smallest diameter, and the lower or base member b^4 is of the 15 greatest diameter.

As is illustrated in Fig. 3, the lower member b' enters and has sliding movement in the next lower member b^2 , and the downward movement of the member b is regulated by placing a collar 32 on said member at a suitable point for engagement with the upper end of the member b^2 when the body is at its lowest point. When the body is to be raised, the upper member b is carried upward 25 a suitable distance and is held in adjusted position by a set-screw 33, passed through the member b^2 to an engagement with the extension-section b' of the member b .

The member b^2 at its lower end is screwed 30 into the upper end of the next lowest member b^3 , as is shown at 34 in Fig. 5, and the lower end of the said member b^3 is screwed into the upper end of the base member b^4 , as is shown at 35 in the same figure.

As will be observed from Figs. 1 and 5, the 35 base member b^4 is hexagonal in cross-section and is provided with a bottom 36, having a threaded opening centrally produced therein, and a plate 37 is made to engage with the bottom portion of the base member b^4 , said 40 plate being provided with a central plain opening 38, through which the threaded end of a thumb-bolt 39 or its equivalent is passed into the threaded opening in the bottom 45 36 of the base. By tightening up the bolt 39 the plate 37 is held rigidly against the bottom of the base member b^4 of the said standard B.

The base member b^4 is provided in alternate 50 panels with upper and lower apertures 37^a, (shown in Figs. 5 and 6,) and the plate 37 is provided with downwardly and outwardly extending arms 40, three in number. The outer ends of the said arms are preferably 55 horizontal, and the horizontal portions of the arms have apertures 41 made therein. When the plate 37 is properly fastened upon the base member b^4 of the standard B, an arm 40 will be opposite each apertured panel 60 of the said base-section, as is clearly shown in Fig. 6.

The legs C for the standard are three in number and may be of any desired shape or configuration; but each leg at its lower portion is provided with a downwardly-extend-

ing pin 42, which enters an aperture 41 in an arm 40. Each leg at its inner vertical edge is provided, preferably, with three flat bearing-plates 43, arranged usually at equal distances apart, which bearing-plates when the 70 legs are in position engage firmly and smoothly with the outer faces of the apertured panels of the said base member b^4 . Pins 44 are made to extend upwardly and outwardly from the bearing-plates 43, and 75 when the legs are placed in position to support the standard the pins 44 are made to enter the apertures 37^a of the base member b^4 , which apertures are given an upward inclination, as is indicated in Fig. 5. Thus 80 when the plate 37 has been loosened the pins 44 of the legs are passed into the apertures 37^a in the said base member b^4 , and then the pins 42 at the bottom portion of the legs are made to enter the apertures 41 in the arms 85 40, extending from the plate 37, and when the belt 39 is tightened it is obvious that the legs will be firmly held in their set position and yet may be very quickly and conveniently removed therefrom. 90

The entire mechanism is of a simple character, and the parts can be quickly assembled or quickly separated, and when separated the parts can be placed in a very small box and conveniently carried. Furthermore, the 95 body of the candelabrum may be adjusted to quite a height, if desired, and the standard is of such construction as to hold the body A securely in the position to which it is adjusted. 100

Having thus described my invention, I claim as new and desire to secure by Letters Patent—

1. In a candelabrum, a cruciform body comprising a transverse member and upper and lower longitudinal members, detachable 105 from each other, and a single fastening device for securing said members together, said members having socket-tubes extending through them, the bores of which tubes are 110 conical, being of least diameter at their bottom ends.

2. In a candelabrum, a cruciform body comprising a transverse member and upper and lower longitudinal members, detachable 115 from each other, means for locking the said members together, a standard constructed in adjustable and separable members, a vertical post connected with the under surface of the lower longitudinal member of the body 120 at the upper portion thereof, the said post engaging the upper member of the standard for revolvably supporting the body upon the standard, the said body being at an angle to the post, a series of socket-tubes extending 125 through the said body at an angle thereto being in a vertical position when the body is in place on the standard, and objects provided with shanks for engaging the said socket-tubes. 130

3. In a candelabrum, a cruciform body comprising a transverse member and upper and lower longitudinal members detachable from each other, a fastening device for all of the members, the said fastening device being carried by the transverse member and arranged for locking engagement with the upper and lower longitudinal members, socket-tubes arranged in a single line one above the other on the longitudinal members of the body, and similar socket-tubes arranged side by side on the transverse member, the said tubes extending above and below the upper and lower faces of said members, and having tapering bores smallest at the bottom, and objects adapted to be carried by the body and having tapering shanks which enter said socket-tubes, and are held in place by frictional engagement therewith.
4. In a candelabrum, a cruciform body comprising a transverse member and upper and lower longitudinal members, the transverse member being provided with upper and lower openings at its back portion, lips extending from the inner ends of the upper and lower longitudinal members, which lips respectively enter the said upper and lower openings in the transverse member, and locking devices at the rear of the transverse member, in locking engagement with it and the lips of the upper and lower longitudinal members.
5. In a candelabrum, a cruciform body comprising a transverse member and an upper and a lower longitudinal member, each member being provided with rearwardly-extending flanges at its side edges, the transverse member being also provided with centrally-located openings in its upper and its lower flanges, and the upper and the lower longitudinal members being provided with lips adapted to enter the said openings in the transverse member of the body, a bolt passed through the transverse member from the front between the openings therein to an engagement with the walls of recesses produced in the opposing ends of the said lips, each of the lips being provided with an aperture in vertical alinement with its recess, a washer having an opening to receive the threaded portion of the bolt and having also pins which enter the apertures in the lips, and a nut which is screwed upon the said bolt to an engagement with the said washer.
6. In a candelabrum, a cruciform body consisting of a transverse member, upper and lower longitudinal members removably connected with the transverse member, locking devices for the said members, located at the rear of the body, a rearwardly-extending flange at the side edges of each of the said members, which flanges are provided with inward projections at their rear ends and grooves in said projections, and ornaments for the outer end portions of the said members, which ornaments are provided with pins adapted to be slid into the spaces between the rear of the said members and the projecting portions of their flanges.
7. In a candelabrum, a cruciform body the members whereof are provided with rearwardly-extending side flanges having inwardly-extending horizontal projections at their rear ends, ornaments for the outer end portions of the members, pins carried by the said ornaments, which pins enter the spaces between the rear faces of the members and the projections from their flanges, and socket-tubes having tapering bores, which tubes are secured to the said body members in single lines, extending both above and below the said members.
8. In a candelabrum, a cruciform body and a standard upon which the said body is removably and revolvably mounted, the said standard being constructed in separable and adjustable sections, the base member of said standard being polygonal in cross-section, legs for supporting the standard, and means for detachably securing the legs to the base member of the standard, said means including projections on the legs adapted to engage openings in sundry of the side faces of said base member.
9. In a candelabrum, a body and a standard therefor, the said standard being provided with a base polygonal in cross-section, sundry of the side faces of the said base having upwardly-inclined apertures therein, a plate located at the bottom of the said base, means for securing said plate to the bottom of the base, the plate being provided with arms extending outwardly therefrom, which arms have apertures therein, and legs corresponding in number to the number of arms on said plate, the said legs having pins which enter the apertures in the arms of said plate, bearing-plates secured to the inner vertical portions of said legs, and pins extending upwardly from sundry of said plates, which pins are adapted to enter the apertures in the base of the standard, for the purpose set forth.
